CHARLES EMILE HEIBIG, OF MENNECY, FRANCE

INTERNAL-COMBUSTION ENGINE OF THE TWO-STROKE TYPE

Application filed August 24, 1928, Serial No. 301,870, and in Germany August 31, 1927.

Engines of the two-stroke type are already known in which the gas supply pump is disposed in the power cylinder. Such apparatus comprise cylinders having different bores coaxing with respective parts of a given piston having the corresponding diameters, said piston being connected with the piston rod. In this manner the gas supply pump consists of the large diameter part of the piston coaxing with the corresponding bore of the cylinder.

The present invention relates to an engine of the two-stroke type in which the gas supply pump is disposed in the power cylinder, but on the contrary to the known devices, the cylinder bore is uniform throughout its entire length. In this case the pre-compression of the fuel gas mixture is obtained by the relative displacements in the cylinder, of a piston which is controlled by the piston rod and which controls the admission ports, and also of a second piston which is connected with the first by an elastic device and which is provided with an automatic valve connecting the explosion chamber with the chamber of variable volume comprised between the said pistons.

In the appended drawings and by way of example:

30 Figs. 1, 2 and 3 show respectively according to two vertical sections in the 90° relation and in various positions, the essential parts of an engine constructed according to the characteristics of the invention.

35 Figs. 4 and 5 relate to modifications which are in section.

According to the invention, the piston which is movable in the cylinder 1, is made in two parts which are movable with reference to one another in such manner as to form between them a compression chamber 2 of variable capacity. One of the said parts 3 is mounted in the known manner upon the pin 4 of the end of the piston rod. The other part 5 also forms a piston and constitutes the movable wall of the explosion chamber 6. The said part 5 is provided with an automatic valve 7 connecting the explosion chamber 6 with the chamber 2 of variable volume which is formed between the

parts 3 and 5 in virtue of their relative displacements. A spring 8 of determined tension connects together the members 3 and 5, and urges them apart.

The explosion chamber 6 comprises a poppet valve 9 (or a valve sleeve as shown in Fig. 5) which is suitably controlled. The cylinder 1 also comprises the admission ports 10 controlled by the displacement of the part 3 as well as an equi-pressure groove 11 whose function will be further specified.

The operation is as follows:

Let it be supposed that the piston rod head is at the upper dead centre, and that the explosion has just taken place (Fig. 1).

The two parts 3—5 of the piston are also at the upper dead centre in the cylinder 1. The said parts 3—5 have the minimum distance apart, and hence the chamber formed between the two has the minimum volume. The spring 8 connecting the two parts is at its maximum compression. The automatic valve 7 is obviously pressed upon its seat by the pressure of the gas which now begins to expand. The whole combination descends in the cylinder until the piston rod head attains the position OE—OA.

At this time the exhaust valve 9 opens, and the part 3 of the piston uncovers the admission ports 10.

The reduction of the pressure which is exercised upon the piston 5 and which results from the exhaust stroke, permits the expansion of the elastic device 8, so that the distance between the parts 3 and 5 will increase, the part 5 continuing to descend. The volume of the intermediate chamber 2 increases, and the resulting vacuum produces the suction of the combustible mixture through the ports 10. Fig. 2 shows the relative positions of the several parts of the engine at the time at which the piston rod head has cleared the lower dead centre and the part 3 of the piston has commenced to rise.

The said part 3 closes the ports 10 and shuts off the gas admission when the piston rod head attains the point F. A. Shortly after (position FE) the exhaust valve 9 is closed, and this permits the part 5 of the piston to

make contact with the lower part of the combustion chamber 6 (Fig. 3). The said part 5 is thus held in the fixed position, while the other part 3 moves towards the upper dead centre. The part 3 acts as a piston which compresses the gas mixture and also the spring 8. When the compression attains a given value, the automatic valve 7 opens; the gas mixture is driven into the explosion chamber 6 in which the part 3 of the piston compresses the said mixture to the definite degree before it is ignited.

10 The several parts have now resumed their relative positions as shown in Fig. 1, and the 15 cycle of operations recommences, producing one explosion per revolution of the driving shaft.

15 The equi-pressure groove 11 has for its object to permit, during the power stroke 20 (Fig. 1) the expansion of the fresh gas under pressure contained in the space 2 between the parts 3 and 5 of the piston.

25 This expansion prevents the discharge of said gas into the main admission conduit when the movable part 3 uncovers the parts 10. From a constructional standpoint, the parts 3 and 5 are provided with the annular grooves 12 and 13 by which the corresponding ends of the spring 8 may be secured. In 30 the part 3 is formed an axial chamber 14 which is adapted to receive the rear end, and also the spring, of the automatic valve 7, whose seat may be placed upon the part 5.

35 On the outer end of the said part 5 is formed the annular flange 15, and at the end of the stroke the said flange engages a corresponding groove 16 in the cylinder head. The whole device thus forms a cushion arrangement, due to the compression of the 40 gas which takes place between the said parts. This disposition obviates the mechanical shocks at the end of the stroke. For a like purpose, the lower part 3 carries at the top an extension 17 coacting with the other part 45 of the piston 5. The annular flanges 19 extending from the respective parts 3 and 5 may even be employed (Fig. 4), and said flanges will shut off a gas cushion coacting with the 50 face of the other part of the piston for damping purposes. The spring 8 may be dispensed with in the case of engines of the rotary type.

I claim:

1. An internal combustion engine of the 55 two stroke type, including a cylinder, a lower piston reciprocating therein, an upper piston reciprocating in said cylinder, resilient connecting means between the pistons, an upper exhaust port, a lower admission port, and means providing for the expansion of the gas between the pistons during the power stroke.

60 2. An internal combustion engine of the two stroke type, including a cylinder, a lower 65 piston reciprocating therein, an upper pis-

ton reciprocating in said cylinder, resilient connecting means between the pistons, an upper exhaust port, and a lower admission port, the said cylinder having an expansion groove formed therein to allow the gas between the two pistons to expand during the power stroke.

3. An internal combustion engine of the two stroke type, including a cylinder, a lower 70 piston reciprocating therein an upper piston reciprocating in said cylinder, resilient connecting means between the pistons, an upper exhaust port, a lower admission port, the said cylinder having an expansion groove formed therein to allow the gas between the two pistons to expand during the power 75 stroke, and a stop limiting the upward movement of the upper piston.

4. An internal combustion engine of the two stroke type, including a cylinder, a lower 80 piston reciprocating therein, an upper piston reciprocating in said cylinder, resilient connecting means between the pistons, an upper exhaust port, a lower admission port, the said cylinder having an expansion groove 85 formed therein to allow the gas between the two pistons to expand during the power stroke, a stop limiting the upward movement 90 of the upper piston, and means carried by the opposing faces of the pistons to provide 95 a cushion effect between them.

In testimony whereof I affix my signature.
